BOBBIN OR YARN SUPPORT

Harald L. Amrhein, Woonsocket, R. I., assignor
to American Paper Tube Co., Woonsocket, R. I.,
a corporation of Rhode Island

Application July 9, 1943, Serial No. 494,021

8 Claims. (Cl. 139—207)

This invention relates to improvements in bobbins or yarn-supporting cores for use in the shuttles of looms.

One object of the present invention is to provide a bobbin or yarn-support having a smooth exterior surface not subject to splitting, splintering or becoming dented or roughened and more durable in use than the common wooden bobbins employed with loom-shuttles.

Another object is to provide a bobbin of the type indicated comprising a paper or fiber tubular barrel and a molded plastic head rigidly secured thereto.

Another object is to provide a bobbin of the type indicated embodying a plastic head at its end secured against either rotary or longitudinal movement relatively of the barrel.

Another object is to provide a bobbin of the type indicated having a metal ferrule enclosing the end of the barrel and head to provide a smooth finished surface resistant to wear.

Another object is to provide a bobbin of the type indicated in which the ferrule is rigidly attached to the barrel and head to prevent relative movement therebetween.

Another object is to provide a head for a bobbin of the type indicated having holding rings on its periphery so constructed and mounted as to prevent their turning thereon.

Another object is to provide a bobbin of the type indicated which is of light weight, simple construction and economical to manufacture.

Further objects of the invention are set forth in the following specification which describes a preferred form of construction of the bobbin, by way of example, as illustrated by the accompanying drawing. In the drawing:

Fig. 1 is a longitudinal view of a bobbin incorporating the novel features of the present invention and showing the tapered form of the paper tube forming the barrel and the molded plastic head rigidly attached to one end thereof;

Fig. 2 is a part-sectional view of the end of the bobbin showing the cooperating tapered faces on the tube and head and the metal ferrule for sheathing the end of the bobbin and attaching the head to the tube;

Fig. 3 is a transverse sectional view on line 3—3 of Fig. 2 showing one of the split rings on the head and the stop or detent between ends of the ring for preventing it from turning on the head;

Fig. 4 is a part-sectional view of the butt end of the bobbin showing a modified form of head in which the rings are molded thereinto; and

Fig. 5 is a transverse sectional view on line 5—5

of Fig. 4 showing the recesses on the interior of the rings into which the molded plastic of the head projects to lock the rings against turning on the head.

5 The present invention relates generally to bobbins on which weft or filling yarn is wound for use in the shuttles of looms. The present improved bobbin comprises a barrel constituted by a tube of fibrous material having a head at one end formed of molded plastic. A metal ferrule sheathes the end of the bobbin and engages with the head and tube to prevent relative rotary and longitudinal movement therebetween. Mounted on the periphery of the head are holding rings for engagement with the clamping jaws in the loom-shuttle and the rings and head are so constructed as to prevent relative movement therebetween.

20 Referring to Figs. 1 to 3 of the drawing, the bobbin comprises a fiber or paper tube 2 having a frusto-conical flange 3 flared outwardly at one end. The tube 2 may be of any suitable shape and in the form shown it is tapered longitudinally with the conical flange 3 flaring outwardly at its butt end. The tube 2 may be composed of paper or similar fibrous material such as molded or pressed pulp. For example, the tube 2 may be constructed by winding or wrapping a paper or fiber sheet or sheets around a mandrel of suitable form with the superimposed layers cemented together with an adhesive. The conical flange 3 at the butt end of the tube 2 may be formed as the sheet material is wound on the mandrel or it may be produced after the tube has been completed by expanding its end to conical shape. As shown most clearly in Fig. 2, the outer peripheral face of the flange 3 is of true conical form while its inner face may be slightly rounded.

25 The head 5 is in the form of an annulus or sleeve surrounding the butt end of the tube 2 and preferably composed of a suitable thermosetting plastic molded to the desired shape and size. The head 5 has a conical counterbore 6 at its end engaging the conical flange 3 on the tube 2 to prevent its rearward movement therealong and a series of longitudinally-extending ribs 7 on its inner periphery which are indented into the peripheral surface of the tube 2 and interlocked therewith to prevent relative rotation therebetween. The outer periphery of the head 5 is 30 formed with an annular recess 8 adjacent its rearward end and a plurality of longitudinally-spaced grooves 9 of semi-circular form in cross-section positioned forwardly of the recess. Each groove 9 extends throughout the greater portion 35 of the circumference of the head 5 with an abut-

ment 10 between its ends. The abutments 10 in the separate grooves 9 are arranged in angular equi-spaced relationship around the periphery of the head 5 as shown in Fig. 3. A split wire ring 11 is mounted in each of the grooves 9 in the head 5 with its ends engaging the opposite sides of the appropriate abutment 10 to prevent the ring from turning on the head.

The ferrule 15 may be formed of suitable thin sheet metal, being arranged to sheathe and protect the butt end of the bobbin and the adjacent inner and outer peripheries of the tube 2 and head 5, respectively. The ferrule 15 has an annular portion or sleeve 16 extending into the end of the tube 2, an annular portion 17 enclosing the rearward periphery of the head 5 and an intermediate connecting portion 18 abutting the end of the head and tube. The annular portion 16 of the ferrule 15 is staked to the tube 2 at a series of points spaced around its periphery by means of sharp prongs or projections 19 which indent the tube to rigidly connect the ferrule thereto. At the forward end of the annular outer portion 17 of the ferrule 15 is an inwardly-directed flange 20 projecting into the recess 8 in the head 5. The annular portions 16 and 17 of the ferrule 15 thus are fixedly attached respectively to the inner periphery of the tube 2 and the outer periphery of the head 5.

The parts of the bobbin are assembled by sliding the molded plastic head 5 along the tapered paper tube 2 and forcing it rearwardly until its conical counterbore 6 engages snugly with the conical flange 3 on the tube. The rearward movement of the head 5 on the tube 2 acts to cause its longitudinally-extending ribs 7 to indent and bite into the tube 2 to interlock it therewith to restrain it from turning on the tube. After the head 5 has been assembled on the tube 2 the ferrule 15 may be applied and its annular portion or sleeve 16 staked to the tube at a series of spaced points therearound by driving a pointed tool through its cylindrical wall to indent the projections 19 into the material of the tube. The forward end of the portion 17 of the ferrule 15 is forced down into the recess 8 in the head 5 by a spinning or rolling operation to adapt the flange 20 to fixedly secure the head in position on the tube with its conical counterbore 6 in firm engagement with the conical flange 3 thereof. The split wire rings 11 may be snapped onto the head 5 either before or after the head is attached to the tube 2. The rings 11 are seated in the grooves 9 in the periphery of the head 5 with their ends engaging the opposite sides of the abutments 10 to restrain them from turning on the head.

Bobbins made in accordance with the present invention comprising a paper tube 2 and a molded plastic head 5 provide a smooth exterior surface for receiving the yarn and are far superior to the usual wooden bobbins which are subject to splitting, chipping, splintering, marring and otherwise roughening to cause chafing of the yarn wound thereon. Such abrasions on the surface of a bobbin restrict the free running of the yarn as it is drawn off during the rapid reciprocation of the loom-shuttle and consequently are liable to cause defects in the fabric woven from the yarn. Should the bobbin of the present invention become roughened its smooth finish may be restored readily by buffing, thereby insuring its usefulness for long periods of time. The provision of a head of molded plastic per-

mits economical manufacture of the bobbins in large quantities with no restriction in quality as to the availability of proper materials. By providing properly spaced abutments 10 between the ends of the grooves 9 in the head 5 the gaps in the wire rings 11 are located in staggered relationship around the periphery of the head so that a firm clamping engagement by the jaws in the shuttle is insured to at all times properly position the bobbin therein.

Figs. 4 and 5 illustrate a head 25 of modified construction having continuous holding rings 26 molded into its periphery as inserts. While the rings 26 may have other shapes, preferably they have a rounded outer cross-sectional contour 27 and a flat interior face 28 as shown in Fig. 4. The interior flat faces 28 of the rings 26 are provided with a series of radial recesses 29 into which the plastic flows when the head 25 is molded, whereof to lock the rings against turning on the head. The recesses 29 in the rings 26 may take other forms and the number of recesses may vary, but as shown in Fig. 5 the recesses are of semi-circular shape and each ring has three recesses. Preferably, the rings 26 are arranged with the recesses 29 of adjacent rings spaced in staggered relationship.

With the construction of head 25 illustrated in Figs. 4 and 5 the flat sided rings 26 will not be embedded as deeply into the periphery of the head 5 as when rings of circular cross-section are used so that the radial thickness of the head 25 may be reduced somewhat to adapt it for tubes 2 of larger diameter. The molding of the continuous rings 26 into the periphery of the head 25 and the locking of the rings against turning thereon prevents loosening of the rings on the head so that the bobbin always will be properly positioned in the shuttle in which it is used.

It will be observed from the foregoing specification that the present invention provides a bobbin of improved construction which is of extremely light weight, economical to manufacture and more resistant to chipping and marring than the wooden bobbins commonly in use. It will be observed also that the metal ferrule of the present construction strengthens and reinforces the butt end of the bobbin and provides a smooth finished surface. It will be observed still further that the improved construction of the head prevents displacement of the holding rings thereon so that the bobbin invariably will be properly positioned in the loom-shuttle with which it is used.

While two forms of construction of the improved bobbin are herein illustrated and described, it is to be understood that further modifications may be made in the form and arrangement of its parts without departing from the spirit or scope of the invention. Therefore, without limiting myself in this respect, I claim:

1. A bobbin of the type indicated comprising a tubular barrel having an outwardly-flaring conical flange at its end, an annular head mounted on the barrel and having a conical counterbore engaging the conical flange thereof, and a ferrule having an annular sleeve-portion extending into the end of the barrel and an annular outer portion surrounding the end of the head, said annular portions of the ferrule being fixedly secured to the barrel and head enclosing the ends thereof and holding the conical counterbore in the head seated against the conical flange on the barrel.

2. A bobbin of the type indicated comprising a fiber tube having an outwardly-flaring conical

flange, an annular head of molded plastic mounted on the tube and having a conical counterbore engaging the conical flange thereof, and a metal ferrule having an annular sleeve-portion extending into the end of the tube and an annular outer portion surrounding the end of the head, said annular portions of the ferrule being rigidly secured to the tube and head enclosing the ends thereof and holding the conical counterbore in the head seated against the conical flange on the tube.

3. A bobbin of the type indicated comprising a tube having an outwardly-flaring conical flange at one end, an annular head mounted on the tube and having a conical counterbore engaging the conical flange thereof, said head having an annular recess in its periphery, and a ferrule having an annular sleeve-portion extending into the end of the tube and an annular outer portion surrounding the end of the head, said annular portion of the ferrule extending into the tube being staked thereto and the annular portion surrounding the end portion of the head projecting into the annular recess in its periphery, said ferrule enclosing the end of the tube and head and holding the conical counterbore in the head seated against the conical flange on the tube.

4. A bobbin comprising a tapered tube of fibrous material having an outwardly-flaring conical flange at one end, an annular head mounted on the tube and having a conical counterbore engaging the conical flange thereof and longitudinally-extending ribs indenting the periphery of the tube, and a ferrule having an annular portion extending into the end of the tube and an annular portion surrounding the end of the head, said annular portions of the ferrule being rigidly secured to the tube and head enclosing the ends thereof and holding the conical counterbore in the head seated against the conical flange on the tube.

5. A bobbin comprising a tube having an outwardly-flaring conical flange at one end, an annular head mounted on the tube and having a conical counterbore engaging the conical flange thereof, said head having a series of grooves encircling its periphery, holding rings seated in said

grooves in the head, and a ferrule having an annular portion extending into the end of the tube and an annular portion surrounding the end portion of the head, said annular portions of the ferrule being rigidly secured to the tube and head enclosing the ends thereof and holding the conical counterbore on the head seated against the conical flange on the tube.

6. A bobbin comprising a tapered tube of fibrous material having an outwardly-flaring conical flange at its butt end, an annular head mounted on the tube and having a conical counterbore engaging the conical flange thereof, said head having a series of circumferential recesses in its periphery and longitudinally-extending ribs on its interior indenting the periphery of the tube, a ferrule having an annular portion extending into the end of the tube and an annular portion surrounding the end of the head, said annular portion of the ferrule extending into the tube being staked thereto to secure it in position and the annular portion surrounding the end of the head formed to engage in one of the recesses in its periphery enclosing the end of the tube and head and holding the conical counterbore of the head seated against the conical flange on the tube, and holding rings seated in the other recesses in the head.

7. A bobbin of the type indicated comprising a barrel having an enlarged head at one end, said head having a plurality of peripheral grooves with an abutment in each groove, the abutments in the plurality of grooves being offset angularly with respect to each other, and split rings seated in the grooves with their ends engaging the opposite sides of the abutments to prevent turning of the rings on the head.

8. A bobbin of the type indicated comprising a barrel having an enlarged head of molded plastic at one end, and metal rings molded into the plastic and projecting radially from the periphery of the head, said rings having recesses in their inner peripheries into which the molded plastic of the head projects to lock the rings against turning on the head.

HARALD L. AMRHEIN.
